US0D1040241S

(12) **United States Design Patent** (10) **Patent No.:** **US D1,040,241 S**
(45) **Date of Patent:** **** Aug. 27, 2024**

(54) **PUZZLE BOARD**

(71) Applicant: **Xiaoling Che**, Dangyang (CN)

(72) Inventor: **Xiaoling Che**, Dangyang (CN)

(**) Term: **15 Years**

(21) Appl. No.: **29/910,054**

(22) Filed: **Aug. 15, 2023**

Related U.S. Application Data

(63) Continuation of application No. 29/818,458, filed on Dec. 9, 2021, now Pat. No. Des. 1,024,210.

(30) **Foreign Application Priority Data**

Sep. 26, 2021 (CN) 202111131554.1

(57) **CLAIM**

The ornamental design for a puzzle board, as shown and described.

DESCRIPTION

FIG. 1 is a rear perspective view of a puzzle board, showing my new design;

FIG. 2 is a front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof; and,

FIG. 9 is an enlarged view of portion 9 of FIG. 7.

The broken lines shown in the figures depict portions of the puzzle board which forms no part of the claimed design. The dot-dash lines depict the boundaries of the enlarged view and form no part of the claimed design.

1 Claim, 9 Drawing Sheets
